INCANDESCENT LAMP

Wilfred O. Langille, Chester, N. J., assignor to
The Singer Manufacturing Company, Eliza-
beth, N. J., a corporation of New Jersey

Application May 7, 1937, Serial No. 141,198

3 Claims. (Cl. 176—32)

This invention relates to incandescent lamps and particularly to lamps of that type which are held in their supporting sockets by so-called "bayonet" joints.

5 A lamp of this type is usually formed on its base with one or more lead or solder contacts connected with the lamp filament and each adapted to be engaged by a spring-pressed plunger-pin carried by the lamp socket and connected with 10 a source of electric current.

It has been found that when lamps of this nature are used in places where they are subjected to extreme vibrations, such for example, as on high speed sewing machines, the vibrations cause 15 the spring-plungers to produce a series of hammer blows on the contacts, with the result that the contacts are indented and consequently the electrical connection between the plungers and the contacts is impaired. This causes a make- 20 and-break of the electric circuit and thereby effects arcing between the plunger and the lead or solder contact which results in the melting and consequently the destruction of the contact. Thus, in such installations, two conditions obtain 25 each of which tends to destroy the lead contact; first, the repeated blows of the plungers on the contacts which impairs the electrical connection between the two, and second, the arcing which melts the contacts.

30 In actual practice it has been found, that lamps of this nature, when used, for example on high speed sewing machines, cease to function long before the lamp filament has burned out. Attempts heretofore have been made to overcome this condition by endeavoring to reduce the vibration of the lamp socket. To that end, numerous vibration dampening supports have been proposed for such lamps, but none of them has been entirely successful in overcoming the difficulty and lamps have continued to be destroyed by the continued hammering action of the spring-plungers on the contacts and the consequent arcing between the two.

35 This invention has as an object to overcome the inherent defects of this type of lamp and its supporting socket by providing a lamp which will not be affected adversely by vibration of the socket.

40 Another object of the invention is to provide an improved method of making incandescent lamps whereby the defects of prior lamps are entirely obviated.

45 These objects have been attained by providing on the lamp-base one or more imperforate wear-resisting metallic contacts which will effectively resist both the hammering effect of the plunger-pin and any arcing which may result due to relative movement between the plunger-pin and the contact.

50 With the above and other objects in view, as

will hereinafter appear, the invention comprises the method of manufacture, and the devices, combinations and arrangements of parts herein-after described in connection with the accompanying drawing which illustrates a preferred 5 embodiment of the invention, and one method which may be employed in producing the same.

In the drawing, Fig. 1 is a perspective view of an incandescent lamp embodying the present invention.

10 Fig. 2 is a longitudinal sectional view, partly in elevation, of a lamp bulb showing the incandescent filament and lead-in wires therein.

Fig. 3 is a longitudinal sectional view of a lamp-base sleeve showing the pins which constitute a portion of a bayonet joint adapted to hold the lamp in its socket.

15 Fig. 4 is a sectional view of two eyelets later to be described.

Fig. 5 illustrates a section of the lamp-base 20 sleeve and a closure therefor of insulating material in which the eyelets are embedded.

Fig. 6 is a longitudinal sectional view showing the lamp-base sleeve of Figure 5 cemented to that 25 end of the lamp bulb containing the lead-in wires.

Fig. 7 is a perspective view of two imperforate metallic contact disks later to be described.

Fig. 8 is a view similar to Fig. 6 but showing the lead-in wires stretched tight, trimmed and 30 soldered in the eyelets.

Fig. 9 is a fragmentary sectional view somewhat similar to Fig. 8 but showing the two imperforate metallic contact disks of Fig. 7 secured 35 to the eyelets.

Fig. 10 is a longitudinal sectional view of a bayonet-type lamp socket and a portion of the present improved lamp inserted therein, with the contact disks of the lamp cooperating with the spring-pressed plungers of the socket.

40 Fig. 11 is a side elevation of a modified form of contact disk.

45 Referring more specifically to the drawing the invention is disclosed as embodied in an incandescent lamp comprising an evacuated or gas-filled glass bulb 1, lead-in wires 2 extending therein and supporting a conventional incandescent filament 3. Surrounding the base of the bulb, and secured thereto, as by cement 4, is a metal sleeve 5 which carries oppositely extending radial pins 6 adapted to cooperate with notches 7 in a lamp-socket (see Fig. 10) to maintain the lamp within the socket. The pins 6 and notches 7 constitute a conventional "bayonet" joint common to this type of lamp.

50 Within one end of the sleeve 5 is secured an insulating element 8, preferably of glass, in which are secured, as by moulding or otherwise, one or more metal eyelets 9. These eyelets are formed 55

with substantially flat annular outer surfaces indicated at 9^a.

It may be noted here that the present invention is adaptable to both single contact lamps and multiple contact lamps. The lamp shown in the drawing is of the multiple contact type in which each lead-in wire is connected with a contact button adapted to be engaged by a spring-plunger in the lamp socket, as distinguished from the single contact type in which one of the lead-in wires is grounded on the sleeve about the base of the lamp and the sleeve is suitably connected with the electric circuit.

The lead-in wires 2 are secured within the eyelets 9 and electrically connected thereto by solder 10. As shown most clearly in Fig. 9 imperforate sheet metal contact disks 11 are secured to the flat outer surfaces 9^a of the eyelets 9 and electrically connected with the lead-in wires 2. The disks 11 may be made of any suitable metal which is sufficiently hard to resist the impact of the plunger-pins of the lamp socket and which has a melting point sufficiently high to be unaffected by any arcing which might take place between the pin and the disk due to vibration. Commercial brass has been found ideal for this purpose.

Fig. 10 shows the improved lamp fitted within a socket-member 12 provided with spring-pressed plunger-pins 13 and 14 adapted to engage the metal disk contacts 11. These pins are movably mounted in sleeves 15 secured within the body of the socket-member 12 and are constantly urged outwardly into contact with the disks 11 by coil springs 16. The pins 13 and 14 are connected, respectively, to the positive and negative sides of a suitable electric circuit, as shown, and therefore transmit the necessary current to the lamp.

If desired, the contact disks 11 may be formed with convex outer surfaces as shown at 11^x in Fig. 11.

As hereinbefore stated, this invention also provides an improved method of manufacturing lamps of this nature. This method comprises the various steps now to be described. Having prepared the evacuated or gas-filled lamp bulb shown in Fig. 2, including the lead-in wires 2 and the filament 3, and having provided the sleeve 5, eyelets 9, and disks 11, the parts are ready for assembly. First, the insulating element 8 is placed within the sleeve 5 and the eyelets 9 are secured therein. This may be done by properly positioning the eyelets relative to the sleeve 5 and then moulding the insulating material within the sleeve and about the eyelets 9 and the inner ends of the pins 6 as shown in Fig. 5. Next, the base, comprising the sleeve 5 with the insulation therein, is placed over the end of the bulb containing the lead-in wires and the wires are threaded through the eyelets as shown in Fig. 6. The bulb is then secured in the sleeve, as by cement 4. The next step in the course of assembling consists in stretching or straightening the lead-in wires, trimming them off flush with the outer surfaces of the eyelets and securing them in the eyelets as by filling the eyelet with molten solder as shown in Fig. 8. These taut wires may assist in holding the base and the bulb together.

The final step consists in soldering to the outer ends 9^a of the eyelets, and in electrical contact with the lead-in wires 2, the imperforate hard metal disks 11 as shown in Fig. 9. This may be done by first tinning one side of the disks

11, placing the tinned side on the eyelets 9 and contacting the upper surface of the disks with a heated soldering iron and maintaining such contact sufficiently long to solder the disks to the eyelets.

From the foregoing it will be perceived that this invention provides a lamp well adapted to withstand both the mechanical and electrical forces which heretofore have tended to destroy this type of lamp when subjected to extreme vibrations.

Insofar as I am aware, no one heretofore has provided a lamp of this type having imperforate hard metal contact plates for receiving the thrust of the spring-pressed plunger-pins of the lamp socket. Neither has any one, so far as I know, disclosed a method of manufacturing lamps which permits imperforate metal plates to be secured to the lamp in electrical contact with the lead-in wires after the lamp has been otherwise completed. Certain lamps heretofore have been constructed with relatively hard metal contacts but in each of those lamps, in which the lead-in wires are taut and aid in securing the base to the bulb, the metal contact has been formed with a perforation through which the lead-in wire is drawn taut after the contact plate has been secured to the lamp, the wire thereafter being soldered to the plate at the outside thereof.

Having thus set forth the nature of the invention what I claim herein is:—

1. An incandescent lamp comprising a base consisting of a sleeve, an insulating element substantially closing one end of said sleeve and an open-ended eyelet secured within said insulating element, said eyelet having a substantially flat annular outer surface substantially flush with the outer surface of said insulating element; a bulb secured within said base; a filament within said bulb; a plurality of lead-in wires connected with said filament, one of said wires being electrically connected with said eyelet; and a pre-formed imperforate wear-resisting contact plate secured to said outer surface of the eyelet and electrically connected with the said one of said lead-in wires.

2. An electric lamp comprising a glass bulb having a neck, a lamp-filament within said bulb, lead-in wires extending through said neck into said bulb and connected to said filament, a lamp-base sleeve secured to said neck, an insulating head within the contact end of said sleeve, a solder-containing lead-in terminal eyelet anchored in said insulating head, one of said lead-in wires being embedded in the solder in said eyelet, and a wear-resisting contact disk of metal harder than the solder in said eyelet soldered to and covering the outer end of said solder-containing eyelet.

3. An electric lamp comprising a glass bulb having a neck, a lamp-filament within said bulb, lead-in wires extending through said neck into said bulb and connected to said filament, a lamp-base secured to said neck, an insulating head at the contact end of said lamp-base, a solder-filled lead-in terminal eyelet, having a flaring solder-receiving mouth and a reduced neck, anchored in said insulating head, one of said lead-in wires being embedded in the solder in said eyelet, and a pre-formed contact disk of wear-resisting metal secured to and covering the flaring mouth of said eyelet.

WILFRED O. LANGILLE. 75
